PROCESS FOR REMOVING SHALE FROM A
NATURALLY OCCURRING BORATE

George A. Connell, San Pedro, and John P. Raso, Boron, Calif., assignors to Pacific Coast Borax Company, a corporation of Nevada

No Drawing. Application May 9, 1938, Serial No. 206,846

3 Claims.

(Cl. 209—6)

This invention relates to the removal of insoluble impurities from naturally occurring borates in sufficient degree to give a merchantable product.

Most borate deposits are believed to have been formed by the drying up of lakes, the waters of which contain borates, or by the deposition of sodium or calcium borate in old sedimentary shale beds. These borates generally are sodium tetraborate decahydrate, sodium tetraborate tetrahydrate, calcium sodium borate such as ulexite, or calcium borate such as colemanite. In the deposition of these various borates fine mud is generally included with the crystals. This mud, under the conditions associated with the deposit, becomes hardened into the form of shale. The result is that practically all the deposits are not deposits of pure borates but have associated with the borates considerable insoluble impurities in the form of shale. This shale may be calcareous or agrillaceous and is generally rather hard.

Due to the presence of these insoluble impurities, generally in the form of shale, borates as mined cannot be used without purification of some sort. Usually this is done by dissolving the borate, if it is a sodium borate or decomposing with sodium carbonate if calcium borate and filtering out the mud and then crystallizing the sodium borate. Other means of improving the borate are in use but all methods are rather expensive. It has been thought that if the shale impurities could be softened by water so as to form a slime this slime could be separated from the coarser borate crystals by hindered settling, screening or decantation. However, it has been found that the shale occurring along with the borates is generally bound together with small amounts of the borates and that this shale ordinarily will not slime when soaked without dissolving such amounts of the borates as to preclude such practice as a commercial operation.

It is an object of our invention to produce a simple and efficient method or process whereby the shales and other earthy matter occurring in borate ores may be readily separated and removed from the ore in such a manner that commercially pure borate may be produced at low cost and expense.

We have discovered that if a mixture of natural occurring borate, such as tincal, ulexite, colemanite or the like, and the shale be exposed to a rubbing action in a cylinder containing rubber covered balls or rods with a saturated solution of the borates, then a large ma-

8

500 cc. of saturated borate solution for fifteen minutes.

5	Analysis of original ore	Analysis after concentrating	
		Percent	Percent
Calcium borates		67	98
Water insolubles		33	2

- 10 10 This concentration was accomplished by recovering 98% of the original borate mineral and making a relatively pure calcium borate product.

15 The above outlined method provides a satisfactory commercially feasible way of separating impurities from naturally occurring borate ores of a shaley nature without dissolving or decomposing the borates as has been the practice in the past.

20 It is to be understood that while we have herein described and illustrated certain preferred procedures to be followed in the practice of this invention, the invention is not limited to the precise operations described above, but includes within its scope such changes as may fairly come 25 within the spirit of the appended claims.

We claim as our invention:

1. The method of recovering borate from its ore which includes, finely crushing the ore, introducing the crushed ore into saturated solution of the borate, agitating the mixture in the presence of yieldable surfaced attrition members, and separating the solid borates from the slimes resultant from the mixture. 5

2. The method of recovering borate from its ore which consists in, grinding the ore to approximately 9 mesh, mixing the ground ore with a saturated solution of the borate, agitating the mixture in the presence of yieldable surfaced attrition members and screening the resultant mixture to separate the particles of borate from 15 the mixture.

3. The method of recovering borate from its ore which consists in crushing the ore, forming a saturated solution of the ore, mixing the crushed ore with the saturated solution, agitating the mixture and separating the borate crystals from the resultant slimes. 20

GEORGE A. CONNELL.
JOHN P. RASOR.
